US00D650556S

(12) United States Design Patent
Anderson et al.

(10) Patent No.: US D650,556 S
(45) Date of Patent: * Dec. 20, 2011

(54) CONFECTION

(75) Inventors: Brent A. Anderson, Lincoln Park, NJ (US); Kelli Babich, Hackettstown, NJ (US); Jason Greer, Hackettstown, NJ (US)

(73) Assignee: Mars, Incorporated, McLean, VA (US)

() Term: 14 Years

(21) Appl. No.: 29/388,867

(22) Filed: Apr. 4, 2011

Related U.S. Application Data

(62) Division of application No. 29/357,973, filed on Mar. 19, 2010, now Pat. No. Des. 637,786.

(51) LOC (9) Cl. 01-01

(52) U.S. Cl. D1/112; D1/127

(58) Field of Classification Search D1/100-199; D30/160; D21/385-386; D24/101-104; D28/8.1; D11/90; 426/3-6, 76, 87, 89, 94-95, 426/100-104, 122, 128, 136, 138-139, 144, 426/249, 274, 293, 302, 305-307, 383, 438-442, 426/464-474, 460, 450-451, 496-497, 502-504, 426/512, 515-518, 543, 557, 549-550, 556, 426/559, 514, 660, 623, 619, 805, 806, 808, 426/499, 572; 428/15

(57) CLAIM

The ornamental design for a confection, as shown and described.

DESCRIPTION

FIG. 1 is a perspective view of a confection showing our new design;

FIG. 2 is a front view of the design shown in FIG. 1;

FIG. 3 is a rear view of the design shown in FIG. 1;

FIG. 4 is a left side view of the design shown in FIG. 1;

FIG. 5 is a right side view of the design shown in FIG. 1;

FIG. 6 is a top view of the design shown in FIG. 1;

FIG. 7 is a bottom view of the design shown in FIG. 1;

FIG. 8 is a perspective view of a confection showing our new design according to a second embodiment;

FIG. 9 is a front view of the design shown in FIG. 8;

FIG. 10 is a rear view of the design shown in FIG. 8;

FIG. 11 is a left side view of the design shown in FIG. 8;

FIG. 12 is a right side view of the design shown in FIG. 8;

FIG. 13 is a top view of the design shown in FIG. 8; and,

FIG. 14 is a bottom view of the design shown in FIG. 8.
